(57) CLAIM

The ornamental design for a golf towel, as shown and described.

DESCRIPTION

FIG. 1 is a front side view of a golf towel according to a first embodiment;

FIG. 2 is a back side view of the towel according to the first embodiment;

FIG. 3 is a left side view of the towel according to the first embodiment;

FIG. 4 is a right side view of the towel according to the first embodiment;

FIG. 5 is a top view of the towel according to the first embodiment;

FIG. 6 is a bottom view of the towel according to the first embodiment;

FIG. 7 is an enlarged fragmentary perspective view of the front side of the towel according to the first embodiment;

FIG. 8 is a front side view of a golf towel according to a second embodiment;

FIG. 9 is a back side view of the towel according to the second embodiment;

FIG. 10 is a left side view of the towel according to the second embodiment;

FIG. 11 is a right side view of the towel according to the second embodiment;

FIG. 12 is a top view of the towel according to the second embodiment;

FIG. 13 is a bottom view of the towel according to the second embodiment; and,

FIG. 14 is an enlarged fragmentary perspective view of the front side of the towel according to the second embodiment. The different types of stippled shading show contrast in appearance between portions of the claimed design. The broken lines shown in the figures represent portions of the golf towel that form no part of the claimed design.
